(57) **CLAIM**

We claim the ornamental design for a battery, as shown and described.

DESCRIPTION

FIG. 1 is a perspective view showing our new design; FIG. 2 is a front view of the embodiment shown in FIG. 1, the rear view being a mirror image; FIG. 3 is a top view of the embodiment shown in FIGS. 1-2; FIG. 4 is a bottom view of the embodiment shown in FIGS. 1-3;

FIG. 5 is a right side view of the embodiment shown in FIGS. 1-4;

FIG. 6 is a left side view of the embodiment shown in FIGS. 1-5; and,

FIG. 7 is a perspective view of the embodiment shown in FIGS. 1-6, with the terminal cover removed in order to show features not apparent in the other views.

The broken lines in FIG. 4 are included for the purpose of illustrating a portion of the battery that forms no part of the claimed design.
